FUEL DISTRIBUTION SYSTEM FOR HIGH-TEMPERATURE PEBBLE BED FURNACES

Frank M. Wolf, Madison, Wis., assignor to Wisconsin Alumni Research Foundation, Madison, Wis., a corporation of Wisconsin

Application July 11, 1944, Serial No. 544,446

6 Claims. (Cl. 23—277)

1

This invention relates to an improved means for delivering fluid fuel under pressure to a high temperature locus within a high-temperature furnace of the "pebble bed" type. In its preferred embodiment it resides in an improved fluid fuel inlet member for a gas reaction furnace of the type described and claimed in U. S. application Serial No. 498,896, filed August 16, 1943, by Farrington Daniels and William G. Hendrickson jointly with the present applicant. Reference 10 also is made to application Serial No. 549,705, filed August 16, 1944, by Farrington Daniels and William G. Hendrickson, and to application Serial No. 538,898, filed June 6, 1944, by Farrington Daniels.

In the type of gas reaction furnace just referred to two pebble beds (for preheating a combustion-supporting gas to be reacted and for chilling gaseous reaction products and simultaneously conserving heat from the latter) are positioned one above the other in a tubular, thermally insulated vessel, the two pebble beds being separated by a gas-mixing and combustion space provided by the interstices in a body of refractory objects all of which objects are larger than the pebbles constituting said pebble beds and some at least of which are of a size too large to function acceptably as means for the quick interchange of heat but sufficiently large to provide desirably large interstitial spaces for gas mixing and for gas reactions. The gas to be reacted is caused to move through the furnace in such direction that it is preheated by abstraction of heat from the pebbles of the first pebble bed, is passed through the centrally disposed gas-mixing and combustion space, and thence is passed through the second of said pebble beds. For maintaining a predetermined high temperature within said "gas-mixing and combustion space," fluid (e. g., gaseous) fuel under pressure is led thereto by means of water-jacketed fuel inlets which project from the outer (cool) ends of said pebble beds axially (that is, parallel to the major axis of the tubular furnace) through these latter and to or into the centrally disposed gas-mixing and combustion space, their inner ends discharging the fluid fuel in a direction parallel to the major axis of the furnace and hence parallel to the direction of movement of the combustion supporting gas to be reacted in said furnace. The so-discharged fuel, in the aforesaid centrally disposed space, is (1) mixed with the gas to be reacted by the progressive mingling of said fuel and said gas occasioned by the repeated mutual deflection of the streams of fuel and gas by the refractory ob-

2

jects filling said space, and (2) burned in said space.

Because the mixing of the parallel streams of fuel and gas, in the system above described, is a gradual and progressive operation, the axial dimensions of the "gas-mixing and combustion space" of the furnace has to be made relatively long, e. g., considerably longer than that of either of said pebble beds, in order to insure that thorough mixing and the combustion of the fuel are effected before fuel and gas pass into the second of the pebble beds. Moreover, it has been thought necessary to macadamize the assemblage of relatively large refractory objects which 15 fill the gas-mixing and combustion space and to insure that at least a part of the macadamized assemblage was constituted by refractory objects of relatively large size (e. g., 5" or 6" chunks).

The fuel-inlet member constituting the present invention divides the fuel supply (which, as brought into the furnace and as passed through the pebble bed, is initially a single fuel stream having a direction parallel to the major axis of the furnace) into a plurality of smaller streams, 20 and discharges these small fuel streams laterally of the member, that is to say, it discharges the divided fuel streams in directions initially transverse to the direction of movement of the gas to be reacted. The "initial" fuel stream is thermally insulated by fluid coolant during its entire course through the pebble bed, and the ensuing divided fuel streams similarly are thermally insulated until they are ejected from the member. When the fuel being employed is gaseous, 25 as usually obtains, the "initial" stream thereof is given an annular shape and is thermally insulated by means of a central stream of coolant within the fuel stream annulus and an annular stream of the coolant surrounding the fuel stream 30 annulus.

In its preferred embodiment, the fuel inlet member of the present invention comprises three spaced concentric tubular members, e. g., metal pipes, extending from outside an end of the furnace through a portion of the pebble bed filling and to a high-temperature locus therein, the inner ends of the innermost and intermediate pipes being joined to close off the inner end of the annular space therebetween, a metallic member closing the inner end of the outermost pipe and spaced from the joined ends of the innermost and intermediate pipes to provide therebetween a passageway communicating between the interior of innermost pipe and the space between the intermediate and outermost pipes, a plurality of

nipples radially extending through the walls of the intermediate and outmost pipes adjacent their inner ends to provide a plurality of discharge passageways from the space between the innermost and intermediate pipes, means for introducing a fluid coolant into the outer end of said innermost pipe, means remote from the furnace for introducing a fluid fuel into the space between the innermost and intermediate pipes, and means for withdrawing fluid coolant from the outer end of the space between the intermediate and outermost pipes.

When a gaseous fuel and a liquid fuel are to be employed alternately, the fuel inlet member just described is modified by the provision of an axially disposed liquid fuel conduit terminating at its inner end in a plurality of lateral branches so designed as to discharge liquid fuel through the same fuel-ejecting elements employed for ejecting the gaseous fuel: in such event, the fuel-ejecting elements desirably may be tapered toward their exit ends.

By reason of the subdivision of the initial fuel supply stream into a plurality of smaller streams, and by reason of the lateral (e. g. radial) directions of the smaller fuel streams at discharge, it follows that the fuel is more quickly mixed with the gas to be reacted, and is burned, much earlier in the course of the travel of the latter through the gas-mixing and combustion space than obtains in the case of the hereinbefore-described system; this circumstance makes it possible to shorten materially the gas-mixing and combustion space and hence the over-all axial dimension of the furnace, thereby saving heat by diminishing the amount of heat radiated through the tubular wall of the furnace at the hottest zone of the latter and of course effecting a saving of the expensive filling material necessarily used in forming the central portion of the shaft filling. In the operation of the system of the present invention the fuel may be caused to burn in a relatively flat zone normal to the direction of movement of the gas to be reacted (i. e., to provide a sharp line of combustion just above the mixing zone). Also, by reason of the very prompt mixing of the fuel with the gas, the "cracking" of thermally unstable fuel—with resulting deposition of solid carbon and creation of local hot-spots—is minimized or even eliminated.

Other advantages accruing from use of the present system include the following:

(a) the inner ends of the fuel inlet members being "closed" (from the standpoint of the major axis), pebbles cannot work into their ends to close off the fuel supply orifices;

(b) combustion space refractory objects or pebbles may be smaller (say, 2" to 3") than heretofore used (e. g., 6") because mixing of fuel and air is more positively promoted;

(c) using smaller pebbles in the combustion space gives larger surface area per cubic foot of the filling material, and hence permits burning more fuel completely (e. g., "surface combustion" effect).

The fuel inlet members may and preferably do discharge into a mass of relatively large refractory pebbles or pebble-like objects providing relatively large interstices. These large objects may be in a generally horizontally disposed layer within the shaft filling. While the upper and lower surfaces of said "layer" may be parallel planes, either surface thereof may be a convex surface having its nearest approach to the other adjacent said fuel inlet device. In this latter event,

the "angularity" of the convex surface may correspond to the resultant of two opposing forces, viz., the force of the air current passing axially through the bed and the force of the fuel gas streams normal thereto.

The jet velocity of the discharged fuel gas may be varied, as desired, without a corresponding change in the calories introduced per unit of time, either (a) by suitable choice of cross sectional area of the discharge orifices, thereby providing a desired jet velocity, or (b) by diluting the fuel gas with air or an inert gas such as carbon dioxide and forcing an increased amount of the lower caloried mixture through the orifices per unit of time. In case (a), I prefer to give the inner surface of the orifice a conical shape (as indicated for element 19 of Fig. 4 of the accompanying drawings) as an expedient favoring high jet velocity of the gas discharged therethrough.

The invention will, in the following be described more particularly, and with reference to the accompanying drawings, in which

Fig. 1 is a side elevational view, with parts in section, illustrating one embodiment of the invention;

Fig. 2 is a side elevational view, with parts broken away, illustrating a preferred mode of assembling the device as illustrated in Fig. 1;

Fig. 3 is a fragmentary side elevational view of the upper portion of the device as shown in Fig. 1, and illustrating a detail of construction of the latter;

Fig. 4 is a view similar to Fig. 1 but illustrating a modification in which fuel oil may be employed as the fuel as an alternative for gaseous fuel;

Figs. 5 and 6 are perspective views of two forms of nozzles or tips suitable for use in the modification shown in Fig. 4; and

Fig. 7 is an elevational view showing the device of the present invention in operative relationship to the pebble bed of a pebble bed furnace.

In the device illustrated in Fig. 1, 1, 2 and 3 are three concentric pipes spaced to provide passageways 4 (between outermost pipe 1 and intermediate pipe 2) and 5 (between intermediate pipe 2 and innermost pipe 3) for fluids. The top end of pipe 1 extends somewhat above the top ends of pipes 2 and 3, and its bottom end terminates short of the bottom end of pipe 2. The threaded bottom end of pipe 3 extends for a considerable distance below the bottom end of pipe 2. Pipes 3 and 2 are secured together at their tops and at the bottom of pipe 2, and the space between said ends closed off, by filler metal members 6 and 7, respectively. A cover member 8 is secured to the upper end of pipe 1, said cover member being sufficiently spaced from the ends of pipes 2 and 3 to leave therebetween a fluids passageway communicating between the interior of pipe 3 and the space between pipes 2 and 1. At the bottom end of pipe 1 this latter is secured to pipe 2 through, and the space between them is closed off by, filler member 16.

Egress of fluid from the top of the space 5 between pipes 3 and 2 is provided by a plurality of (e. g., four) nipples 9, 9, communicating with the space 5 through openings in the walls of pipes 1 and 2. Said nipples serve also to hold the tops of pipes 1 and 2 rigidly in position with respect to each other. Access of fluid to the bottom of said space is provided by an outstanding threaded nipple 10 communicating with space 5 through an opening in the wall of pipe 2. Egress of fluid

from the bottom of space 4 is provided by an outstanding threaded nipple 11 communicating with space 4 through an opening in the wall of pipe 1.

The complete fluid fuel-introducing device, D, has a length, between outstanding nipple 11 and nipples 9, 9 such that the upper portion of the device may, as shown in Fig. 7, project, with nipples 10 and 11 exposed (accessible), within a pebble bed furnace through a substantial part of a pebble bed and to a locus whereat delivery of fuel gas is desired. Since the depths of such pebble beds are, in turn, determined by a number of variable factors, it is impossible arbitrarily to assign any specific length value with respect to the device; however, it may be noted that the specific device shown in Fig. 7 has a length of approximately 18 inches between nipples 9 and nipple 11, and is adapted to project through a grating 41, 42, of about 1 inch and through a pebble bed, Zone F₁, of approximately 12 inches depth supported on said grate.

Fig. 7, which is not drawn to scale, shows a pair of the fuel inlet devices of the present invention installed in a specific construction of a pebble bed furnace for fixing atmospheric nitrogen. In Fig. 25 7, F₁, F₂ and F₃ taken together represent a shaft filling enclosed within a tubular refractory wall 30, which latter is supported upon a base 31 of heat-resistant concrete. 32 is an outer shell of sheet iron concentrically surrounding and spaced from tubular wall 30, the so provided space being filled with a mass of loose unclassified magnesia insulation 33 supported on base 31. 34 is a centrally domed cover secured along its periphery to the upper edge of shell 32. Cover 34 rests upon the upper end of tubular wall 30, and its domed portion rises above the space enclosed by said wall, providing an open space 37' above the shaft filling. A functionally similar open space 37 is provided in base 31 beneath said shaft filling. The opening 37 in base 31 is bridged at its top by spaced grate bars 41 supporting a water-cooled grate 42; this latter is a coiled iron pipe whose inlet and outlet connections (not shown) pass through base space 37 and base 31 to the outside.

The shaft filling F₁, F₂, F₃ is supported upon said bars 41 and water-cooled grate 42.

Zone F₁ of the shaft filling is composed of a relatively thin layer 43 of refractory pebbles of about 1½-inch size, adjacent bars 41 and grate 42 and, superposed thereon, a bed 44 of refractory pebbles of smaller size, e. g., 3-4 mesh Tyler screen. The layer 43 of somewhat larger refractory pebbles serves to prevent gravitational escape of the smaller pebbles constituting bed 44 through grate 42 and bars 41.

Zone F₂ is a relatively tall column of relatively large refractory bodies, e. g., fused magnesia chunks, ranging in size from ½ inch to 5 inches average diameter. As shown in the drawings, the refractory bodies are disposed in layers according to their sizes, the largest chunks occupying the functionally central part of the column and flanked below and above by successive layers of refractory bodies of progressively smaller sizes.

Zone F₃ is identical with zone F₁ but inverted.

Zones F₁ and F₃ constitute the hereinbefore referred to pebble beds for preheating a gas to be thermally reacted and for chilling gaseous reaction products, while zone F₂ constitutes the "gas-mixing and combustion space."

Fluid fuel-introducing device D is positioned partly within open space 37 and partly in the lower portion of the shaft filling; it extends through bars 41 and grate 42 and zone F₁ of the

shaft filling and somewhat into zone F₂, with egress nipples 9, 9, adjacent a layer of relatively large refractory bodies of the shaft filling. Member 3 is connected to a supply of cooling water and nipple 11 to a water disposal conduit. Nipple 10 is coupled to a fuel gas supply conduit 39.

Fluid fuel-introducing device D' is identical with, but in inverted position with respect to, device D. D and D' are connected to a source of fuel gas under pressure through pipes 38 and 38' and three-way valve V.

B diagrammatically represents an air compressor to the pressure side of which is connected a reversing mechanism R. 38 and 38' are air conduits communicating between open spaces 37 and 37', respectively, and said reversing mechanism R. This latter mechanism is connected to a nitric oxide recovery system (not shown).

When the device is in position in a pebble bed furnace, as illustrated in Fig. 7, with its major axis parallel to the major axis of the furnace, the bottom threaded end of pipe 3 is connected to a suitable source of water (or other fluid coolant) under pressure. Nipple 11 may be connected to any suitable means for disposing of coolant, e. g., to a cooling water spray tower for dissipating heat from the cooling water incident to return of the water to pipe 3 of the device. Nipple 10 is connected to a suitable source of fuel gas under pressure. In use, the fluid coolant flows inwardly through pipe 3, thence into the space between the inner end of pipe 3 and cover member 8, thence outwardly through the space 4, and discharges through nipple 11. Fuel gas is admitted into space 5 of the device by nipple 10 and flows inwardly through said space; at the inner end of said space, the stream of fuel gas is divided into a plurality of smaller streams which are discharged through nipples 9, 9 radially into the pebble bed F₂ in directions initially normal to the direction of movement of the gas being treated in said furnace.

In the use of the assemblage above described, with the setting of reversing mechanism R as shown in Fig. 7, a current of air under pressure is forced, through conduit 38 and open space 37 into and upwardly through the shaft filling F₁, F₂, F₃ and thence through open space 37', conduit 38' and reversing mechanism R to a nitric oxide recovery system or to stack. Simultaneously, by proper adjustment of valve V a stream of fuel gas is forced through pipe 39 to device D which latter subdivides the stream into a plurality of smaller streams which are radially emitted through members 9, 9 into the lower part of zone F₂. Upon reversal of the air current direction, valve V is so adjusted as to stop flow of fuel gas through device D and to cause flow of fuel gas through device D'.

Fig. 2 shows an intermediate stage in the preferred mode of constructing the device shown in Fig. 1.

Openings 12 and 13 are provided in pipes 1 and 2, respectively, said openings being so located, adjacent the ends of the pipes that, when the pipes are assembled in the position shown in Fig. 2, the openings 12 and 13 will be in alignment, with the end of pipe 1 extending somewhat beyond the end of pipe 2. Nipples 9, 9 are then welded to pipe 2 with their bores coinciding with openings 13. The top portion of pipe 1 is severed along a plane passing through the centers of openings 12. Pipe 3 is inserted in pipe 2, their ends are spaced by filler members 6 and 7, and the pipe ends and filler members are united by

welding. The resulting assembly of pipes 3 and 2, with nipples 9, 9 attached to the latter, is inserted in pipe 1 through the upper end thereof and with nipples 9, 9 resting in the lower halves of openings 12. The cover member 8 is secured at the top of the severed top portion of pipe 1 by welding. The resulting closed end portion is placed in position over pipe 1 and reunited to the latter by welding, and nipples 9, 9 are secured to the thus-reunited pipe 1 by welding, as indicated in Fig. 3, thus completing the discharge end of the device.

Nipple 11 is secured by welding to pipe 1 in communication with the opening 14 provided in said pipe. Nipple 13 is secured by welding to pipe 2 in communication with the opening 15 provided in pipe 2. The space between the lower end of pipe 1 and the outer wall of pipe 2 is then closed by welding in filler member 16.

The device illustrated in Fig. 4 is generally similar to that shown in Fig. 1; it differs from the latter in the following structural respects: Within pipe 3 there is positioned a pipe 17 for leading liquid fuel (e. g., fuel oil) inwardly to the plane of fuel gas discharge from space 5. Pipe 17 terminates at its inner end in a plurality (e. g., four as shown) of laterally offstanding branch conduits 18, 18; these latter extend through openings provided in, and are secured to, pipe 3 and substantially across space 5, with their outer, open ends in axial alignment with the fuel gas discharge means from space 5. These latter, elements 18, 18, differ from the nipples 9, 9 of Fig. 1 in that their bores are substantially conical with the bases adjacent pipe 2. Elements 18, 18 are shown as having substantially cylindrical outer surfaces; however, they may, as is indicated in Fig. 6, be given a streamlined contour in the direction of flow of the coolant in order to minimize turbulence in the coolant stream immediately beneath said fuel gas discharge means. Pipe 17 may, as shown, be introduced into the lower end of the device through the packing gland 20 in elbow 21 at the end of pipe 3.

In the operation of the modified device of Fig. 4, gaseous fuel, only, is used during an initial stage of heating of the pebble bed, after which the feeding of fuel gas is stopped and the feeding of fuel oil is commenced. During the feeding of fuel oil to the device, a stream of air simultaneously is fed through nipple 10 into space 5 for the purpose of forming an oil-air mixture for ejection from members 18, 18.

While the preferred form of the fuel inlet member is such that the incoming stream of coolant is enclosed by an annular stream of fuel and the latter in turn is enclosed by an annular stream of outgoing coolant, the structure is operable when so modified that fuel is introduced through the innermost pipe, the incoming stream of coolant is introduced through the space between the innermost and intermediate pipes, and the outgoing stream of coolant makes use of the space between the intermediate and outermost pipes. In such event the lateral branches or nipples for discharging fuel extend through the walls of at least the innermost and outermost pipes, and communication between the inner end of the space between the innermost and intermediate pipes and the inner end of the space between the intermediate and outermost pipes is provided. Such communication desirably may be provided by terminating the inner end of the intermediate pipe short of those of the innermost and outermost pipes.

5 The side wall and/or the inner end wall of the fuel inlet member may, if desired, be provided with an outer covering of suitable heat-insulating material for protecting the metal of the member.

10 The fuel inlet device of the present invention is particularly adapted for use in the following modification of the conventional operation of the nitric oxide furnace: The fuel inlet device and the layer of large refractory chunks into which it discharges are substantially axially centrally located within the shaft filling. During one-half of the complete cycle a current of air is passed upwardly through the shaft filling, while during the succeeding one-half cycle a current of air is passed downwardly through the shaft filling. Fuel gas is discharged through the fuel inlet device for a part, only, of each half cycle, in a total amount suitable to maintain the central portion of the shaft filling at a predetermined temperature, in the following manner: In a situation wherein a complete cycle (upstroke plus downstroke) is of 20 minutes duration and wherein it is necessary to burn fuel gas for six-tenths of the total time, the fuel gas may be admitted during the last 6 minutes of one stroke and for the first 6 minutes of the next succeeding stroke, the fuel gas being turned off for the beginning 4 minutes of the first-mentioned stroke and likewise for the final 4 minutes of the second-mentioned stroke. The furnace system can be so arranged that during the 12 minute period of each complete cycle in which fuel gas is being introduced and burned the gases simultaneously being discharged from the furnace are either wasted to stack or are diverted to a secondary recovery system, while during the other 8 minute period of the cycle the gases discharged from the furnace are conveyed to the primary recovery system for recovery therefrom of their proportionally larger content of oxide of nitrogen. It is to be understood, of course, that the above 12 to 8 ratio is given by way of illustration only, and that the ratio of "fuel gas on" time to the "fuel gas off" time in the complete cycle is adjusted to suit the particular furnace and the conduct of the process therein. In a case where heat losses are relatively low, the ratio may be as low as 3 (or even 2) to 5.

15 50 I claim:

1. A furnace of the "pebble bed" type comprising a tubular shaft, a supporting grating, a stratified series of transverse beds of refractory filling, said series including a centrally disposed bed of relatively large refractory objects and beds immediately above and below the said centrally disposed bed of relatively small refractory objects, said shaft and filling being so constructed and arranged as to provide open spaces above said filling and below said grating, reversible means for alternately directing gases to traverse said shaft into said spaces, reversible means arranged to alternately feed fluid fuel to the top and bottom of said centrally disposed bed, and fuel conduit means in said furnace comprising a fuel conduit extending from one of said open spaces to said central bed, a plurality of laterally extending nozzles communicating with said tubular conduit, a fluid coolant jacket surrounding said fuel conduit, and outlet means for said coolant arranged for extension to the exterior of the furnace.

2. A furnace of the "pebble bed" type comprising a tubular shaft, a supporting grating, a stratified series of transverse gas-traversable beds of refractory filling, said series including a

centrally disposed bed of relatively large refractory objects and beds immediately above and below the said centrally disposed bed of relatively small refractory objects, said shaft and filling being so constructed and arranged as to provide open spaces above said filling and below said grate, reversible means for alternately directing gases to traverse said shaft into said spaces, reversible means arranged to alternately feed fluid fuel to the top and bottom of said centrally disposed bed, and a plurality of fuel feeding means in said furnace each fuel feeding means comprising a fuel conduit extending from one of said open spaces to said central bed, a plurality of laterally extending nozzles communicating with said tubular conduit, a fluid coolant inlet conduit inside said fluid fuel conduit, a fluid coolant jacket surrounding said fuel conduit, and in communication with said inner fluid coolant conduit at that end of the latter which is extended within the furnace, and inlet and outlet means for said coolant arranged for extension to the exterior of the furnace.

3. A furnace of the "pebble bed" type comprising a tubular shaft, a supporting grating, a stratified series of transverse gas-traversable beds of refractory filling, said series including a centrally disposed bed of relatively large refractory objects and beds immediately above and below the said centrally disposed bed of relatively small refractory objects, said shaft and filling being so constructed and arranged as to provide open spaces above said filling and below said grate, reversible means for alternately directing gases to traverse said shaft into said spaces, reversible means arranged to alternately feed fluid fuel to the top and bottom of said centrally disposed bed and a plurality of fuel feeding means in said furnace each fuel feeding means comprising a gaseous fuel conduit extending from one of said open spaces to said central bed, a plurality of lateral gaseous fuel jets communicating with said gaseous fuel conduit, a fluid coolant intake conduit inside of said gaseous fuel conduit, a fluid coolant jacket surrounding said gaseous fuel conduit, and in communication with said inner fluid coolant conduit at that end of the latter which is extended within the furnace, a liquid fuel conduit within said fluid coolant intake conduit, a plurality of laterally offstanding open ended branches extending from the inner end of said liquid fuel conduit through the fluid coolant intake conduit and into discharging proximity to said jets, and

inlet and outlet means for said coolant arranged for extension to the exterior of the furnace.

4. A fuel inlet device, comprising three concentric tubular members, of which the outer tubular member has a closure member at one end and is sealed to the intermediate tubular member at the other end, and of which the intermediate and innermost members extend short of the closure member and are sealed together at such end and also at the end of the intermediate member so as to form an annular space with no communication to the innermost space or to the space between the outer and intermediate tubular members, a plurality of passage members radially extending from adjacent the end of the intermediate tubular member near the closure member from the intermediate tubular member and the annular space between the innermost and intermediate tubes through the outermost tube to provide nozzle passage through said space to the exterior, said outer tube being provided with an opening adjacent that end of said tube removed from the closure end, said intermediate tube being provided with an opening also adjacent the end removed from the closure member, and that end of the innermost tube which is removed from said closure member being open for connection to a source of coolant.

5. The fuel inlet device defined in claim 4, characterized in that a liquid fuel conduit is positioned within and spaced from the walls of the innermost tubular member, which liquid fuel conduit extends short of said closure member and terminates in a plurality of laterally offstanding open-ended branches extending through the innermost tubular member and into discharging proximity to said radially extending passage members, there being as many branches as there are passage members.

6. The fuel inlet device defined in claim 4, characterized in that said radially extending passage members are frustro-conical with the frustrated apices adjacent the outer tubular member, and in that a liquid fuel conduit is positioned within and spaced from the walls of the innermost tubular member, which liquid fuel conduit extends short of said closure member and terminates in a plurality of laterally offstanding branches extending through the innermost tubular member and into discharging proximity to said radially extending passage members and terminating in jet orifices, there being as many branches as there are passage members.

FRANK M. WOLF.
